(57)

CLAIM

The ornamental design for a vaporizer battery, as shown and described.

DESCRIPTION

FIG. 1 is a first isometric view of a first embodiment of a vaporizer battery;

FIG. 2 is a second isometric view thereof;

FIG. 3 is a right plan view thereof;

FIG. 4 is a front plan view thereof;

FIG. 5 is a left plan view thereof;

FIG. 6 is a rear plan view thereof;

FIG. 7 is a top view thereof; and,

FIG. 8 is a bottom view thereof.

FIG. 9 is a third isometric view thereof;

FIG. 10 is an isometric view of a second embodiment of the vaporizer battery;

FIG. 11 is a right plan view thereof;

FIG. 12 is a front plan view thereof;

FIG. 13 is a left plan view thereof; and,

FIG. 14 is a rear plan view thereof.

The broken lines are for the purpose of illustrating portions of the vaporizer battery that forms no part of the claimed design.
